CLAIM

The ornamental design for a motor for curtain controller, as shown and described.

DESCRIPTION

1. Motor for curtain controller

1.1 : Front

1.2 : Back

1.3 : Left

1.4 : Right

1.5 : Top

1.6 : Bottom

1.7 : Perspective

The broken lines shown in the drawings illustrate portions of the motor for curtain controller and form no part of the claimed design.
